SHEET FEEDING MECHANISM

Ward W. Beman, Glendale, Calif., assignor, by mesne assignments, to International Business Machines Corporation, New York, N. Y., a corporation of New York

Application November 24, 1954, Serial No. 470,845

10 Claims. (Cl. 271—41)

This invention relates to sheet feeding mechanism, and especially to apparatus for feeding sheets of substantial thickness, for example, accounting machine cards, at high rates of speed.

In feeding sheets at high rates of speed, it has been suggested to feed the sheets from a supply stack in an overlapped condition, i. e., with each sheet overlapping partially the preceding sheet and being overlapped by the following sheet. The overlapped sheets are separated later at a point in the sheet-handling operation which is spaced from the supply stack.

The rapid feeding of accounting cards to high speed computers presents exceptional problems, because of the very high feeding rates required, e. g., 3,000 per minute, and because of the necessity of avoiding damage to the edges of the cards, which might produce jamming of the cards or errors in the computing mechanism.

An object of the invention is to provide improved mechanism for feeding sheets at very high rates.

Another object is to provide improved means for feeding accounting cards at a very high rate.

Another object is to provide improved mechanism for feeding sheets or cards in an overlapped manner.

Another object is to provide an improved gate mechanism for controlling the overlapped feeding of sheets.

Another object is to provide an improved friction drive mechanism for card feeding means of the type described.

The foregoing objects are attained by providing, at the outlet of a card feeding hopper, a walking gate mechanism including two legs. Each leg is provided with a foot having a side face adapted to engage the leading edges of the cards of the stack and a bottom face adapted to engage the top of a card moving under the gate. The two gates are provided with interspaced toes on their feet, and the toes of each foot move between the toes of the other foot.

Each leg is driven so that its foot moves along a path from a registering position in which its side face engages the lowermost card in the stack forwardly along the path of card movement, then upwardly until it clears the lowermost card, and then backwardly along the path of card movement to a gate position in which its side face engages the stack of cards above the second lowermost card. The legs are connected for eccentric movement with respect to each other and means are provided for driving the legs alternately along paths as described above, the driving means being effective when the foot of one leg is in the registering position to hold the foot of the other leg in the gate position.

The walking gate mechanism is mounted on a frame. The connections between the legs and the frame include a pair of rods spanning the generally U-shaped frame. The legs are provided with slots across their upper ends to receive one of the rods. The other rod passes through openings in the lower portions of the legs and serves as a stop to limit their forward and backward movement. Springs bias the two legs against one side of the stop rod.

The driving means includes a shaft extending through the frame and having journals in the two legs which are eccentric with respect to each other. The frame is mounted on a fixed vertical support by means of a parallelogram linkage so that the frame may move upwardly, parallel to the face of the supply stack of cards, so as to permit different numbers of cards to pass under the gate simultaneously, for example, during starting or stopping the feeding of a stack of cards.

10 A friction roller runs continuously against the bottom card in the stack and tends to drive it forward and through the gate. Suction apparatus is provided for maintaining a subatmospheric pressure on the underside of the bottom card to hold it against the friction roller. As soon as they 15 pass the gate, the cards are engaged by positive pullout rollers.

Other objects and advantages of the invention will become apparent from a consideration of the following specification and claims, taken together with the accompanying drawings.

In the drawings,

Fig. 1 is a somewhat diagrammatic perspective view of a card feeding mechanism embodying the invention;

Fig. 2 is a perspective view similar to Fig. 1 showing 25 certain parts of the mechanism in greater detail, including the walking gate mechanism;

Fig. 3 is an exploded perspective view of the walking gate;

Fig. 4 is an assembled perspective view of the walking 30 gate;

Fig. 5 is a vertical cross-sectional view of the walking gate taken along the line V—V of Fig. 4; and

Fig. 6A to 6F are diagrammatic views illustrating the 35 sequence of movements of various parts of the walking gate during a card feeding operation.

There is shown in Fig. 1 a hopper 1 for receiving a stack of cards 2, which are held down by a weight 3. The hopper 1 is provided near the bottom of one end with an opening 1a, through which cards may be fed from 40 the bottom of the stack. The hopper is tilted slightly toward the opening 1a to facilitate the outward movement of the cards. Below the hopper is located a shaft 4 carrying a rubber friction roller 5 which projects through an opening in the bottom of the hopper, and engages the 45 bottom card of the stack. The shaft 4 is continuously turning in a direction so that the roller 5 tends to feed the bottom card out of the hopper.

The shaft 4 and roller 5 are located in a box 6, under 50 the hopper 1. The pressure in the box 6 is maintained at a sub-atmospheric value by means of a pump (not shown) connected to an outlet 7. The suction so maintained in the box 6 helps to hold the cards against the continuously running roller 5.

The cards feeding from the bottom of the stack 1 pass 55 through the opening 1a under the control of a walking gate mechanism generally indicated at 7, which is described in detail below. Immediately after passing the gate 7, the ends of the cards are engaged by a pair of pullout rollers 8, which are spaced close to the gate 7.

60 The rollers 8 feed the cards across a table 9 to a pair of separating rollers 10. The cards passing across the table 9 are in their overlapped condition, as illustrated at 11 in Fig. 2. The rollers 10 are running substantially faster than the rollers 8, so that they separate each overlapped card from the following cards. The cards may then proceed through any desired apparatus for performing accounting functions, such as card reading, printing or punching mechanisms.

65 The cards are fed endwise from the hopper 1. The spacing between the pullout rollers 8 and the separating friction roller 5 is less than the length of one card.

Walking gate

The walking gate mechanism comprises a vertically extending frame 12, having a U-shaped horizontal cross-section. The frame 12 is pivotally connected to a set of parallelogram links 13, whose opposite ends are pivoted on the lower end of a fixed support 14, which extends parallel to the discharge side of the hopper 1.

Inside the frame 12 are two legs 15 and 16. The leg 15 is shown as having a U-shaped horizontal cross-section, so dimensioned that it fits freely inside frame 12, and the leg 16 has a rectangular horizontal cross-section so dimensioned that it fits freely within the leg 15. At their lower ends, the legs 15 and 16 are provided with feet 15a and 16a (Fig. 5). The feet 15a and 16a are provided with interspaced toes 15b and 16b, the arrangement being such that the toes 15b of foot 15a move between the toes 16b of foot 16a, and vice versa. Each of the toes 15b and 16b has a front face 15e, 16e, adapted to engage the leading edge of the cards stacked in the hopper 1, and a bottom face 15f, 16f, adapted to engage the top of a card 2 which is passing under the gate.

Two rods 17 and 18 are fixed at their ends in the sides of the U-shaped frame 12, and span the space between those sides. The legs 15 and 16 are provided in their upper surfaces with slots 15c, 16c, which receive the upper rod 17. The lower rod 18 passes through suitably formed apertures 15d, 16d in the two legs 15 and 16. Springs 19 and 20 are retained between the frame 12 and the legs 15 and 16, respectively, and bias the lower ends of those legs to the left as viewed in the drawings toward positions in which the right-hand ends of the openings 15d, 16d engage the lower rod 18.

A drive shaft 21 extends freely through the sides of the frame 12, and is journaled in both of the legs 15 and 16. The journal in one of the legs is made eccentric with respect to the journal in the other. In the particular mechanism illustrated, this is accomplished by having the journal in the leg 16 concentric with shaft 21, while the journal in leg 15 comprises a pair of eccentrics 22, fixed on shaft 21 and journaled in the opposite arms of the U-shaped leg 15. Any equivalent mechanism which will cause the legs 15 and 16 to move eccentrically with respect to each other may alternatively be used.

The shaft 21 turns continuously in the direction indicated by the arrow in Fig. 6A. The shaft 21 is driven through a pair of universal joints 23 and 24 (Figs. 1) to accommodate the motion of the eccentrics, and of the frame 12, as described below.

Operation of the walking gate

The operating of the walking gate mechanism can best be understood by reference to the diagrammatic Figs. 6A to 6F inclusive. In these figures, the proportions of various parts are distorted so as to better illustrate the sequence of the various movements.

Fig. 6A shows the mechanism in its starting position, before any card is fed from stack 2. Leg 15 has the face 15e of its toes against the lowermost cards in the stack 2. The leg 16 is at a position so that its foot 16a is slightly higher than the foot 15a. The eccentric journals 22 in leg 15 are arranged so that this difference in height between the two feet is slightly more than the thickness of one card, but substantially less than the thickness of two cards. For example, for handling cards .007" thick, this distance was made equal to .010".

As the shaft 21 turns counterclockwise as viewed in Fig. 6A, the eccentric 22 tends to move the leg 15 to the right with respect to leg 16. The springs 19 and 20 tend to hold both the legs against the rod 18. The result is that the leg which at any instant is being driven to the right with respect to the other leg is forced to the right against its associated biasing spring, the other leg remaining in the position where the right-hand end of its opening 15d or 16d engages the rod 18. In the present instance,

the leg 15 is moved to the right, to the position shown in Fig. 6B, the leg 16 remaining in the position shown in Fig. 6A, with the right-hand end of opening 16d engaging stop rod 18. As leg 15 moves to the right, the lowermost card in the stack 2 follows it, since it is driven by friction roller 5 and is not restrained except by the leg 15. When the leg 15 reaches its right-hand limit of movement, as determined by eccentric 22, the parts have reached the position shown in Fig. 6B. As the eccentric continues to turn, leg 15 is driven upward, until it clears the leading edge of the lowermost card, whereupon that card continues to move forward under the drive of the friction roller 5. Almost as soon as it clears the leg 15, the card reaches the pullout rollers 8, which engage it positively on both its upper and lower surfaces, and drive it forward.

As the shaft 21 continues to rotate, the eccentric 22 reaches the position shown in Fig. 6C. The leg 16 is now the lowermost of the two legs, the leg 15 being raised to .010" above leg 16 by the action of the eccentric 22. Both legs have their toes against the cards in the stack. Leg 16 has its bottom face 16f resting upon the top of the first card which was fed.

The position of the lowermost leg at any instant determines the vertical position of the frame 12 with respect to the stationary support 14. The frame 12 rests, by means of the rods 17 and 18, on the bottoms of the slots 15c and 16c and the openings 15d, 16d. At any given instant, it rests on the bottom of the slot and/or opening in the uppermost one of the two legs. That uppermost leg is supported above the lower leg by the shaft 21 and eccentrics 22. The vertical position of the lower leg is determined by the thickness of the card or cards passing underneath it, and on which it rests.

In the position in Fig. 6C, the lower leg 16 is on the top of one card only. The vertical position of leg 15, above leg 16, is determined by the eccentric 22. The frame 12 rests by means of the rods 17 and 18 on the leg 15. The frame 12 moves vertically to accommodate the thickness of the cards underneath the legs. It is maintained parallel to the face of the stack 2 by the parallelogram linkage 13.

It may be seen, by reference to Figs. 6A, 6B and 6C, that during the time represented by those figures, the lower end of the leg 15 has been driven on a generally elliptical path extending from the position of Fig. 6A, to the right and upwardly and then back to the left and to the position in Fig. 6C. The position of leg 15 in Fig. 6A is hereinafter referred to as the "registering position," and the position in Fig. 6C as the "gate position."

Starting now from the position shown in Fig. 6C, the eccentric 22 continues to turn counterclockwise and tends to push the leg 15 to the left with respect to leg 16. However, leg 15 cannot move to the left, being restrained by the rods 17 and 18. The leg 16 and shaft 21 therefore move backward against the spring 20, reaching the position of Fig. 6D. The leg 16 now follows a path similar to that followed by leg 15 in Figs. 6A to 6C, except that it takes place at a generally higher level, since the lowermost card is now under the gate. As the leg 16 moves to the position of Fig. 6D, the second card in the stack follows it, being driven by the roller 5. As the leg 16 proceeds from the position of Fig. 6D to the position of Fig. 6E, it moves upwardly and clears the leading edge of the second card, which is thereupon pushed out underneath the leg 15, then in its gating position. The leg 16 on reaching the position of Fig. 6E is in the same position with respect to leg 15 as it was in Fig. 6A. However, both the legs and the frame 12 have now been moved upward from their positions of Fig. 6A by an amount equal to the thickness of two cards.

The walking gate has now proceeded through one complete cycle. It continues to repeat the same cycle, rising the thickness of two cards on each repetition of the cycle until a condition is reached where the end of the

lowermost card is passing out from underneath the gate as a new card is fed into it. This situation is illustrated in Fig. 6F. The frame 12 then remains in that position, with the walking gate proceeding through its operating cycle, until almost all the cards in the hopper 2 have been fed out. As the last few cards in the hopper are fed, the gate 12 moves downwardly, accommodating its vertical position to the number of cards passing under it.

Note that in the gate mechanism illustrated, no pushing force is applied to the edge of a card, but is applied to one of the flat surfaces of the card. While the card may be restrained from movement by holding an edge, the restraint is only from the drive imparted through the friction roller 6. By the time the leading edge of the card reaches the positive feeding pullout rollers 8, which engage both opposite surfaces of the card, then the leg 15 or 16, as the case may be, has moved upwardly out of the path of the card and it is no longer restrained. The gate mechanism is thereby effective to feed the cards at a high rate of speed without deforming their edges.

While a preferred embodiment of the invention has been shown and described, other modifications thereof will readily occur to those skilled in the art, and it is therefore intended that the invention be limited only by the appended claims.

What is claimed is:

1. Card feeding mechanism including a gate comprising a pair of legs, each leg having a foot with a side face adapted to engage the leading edges of cards in the stack and a bottom face adapted to engage the top of a card moving under the gate, a set of spaced toes on each foot, said respective sets of spaced toes being interspaced so as to be movable between the toes on the other foot, means connecting said legs for eccentric movement with respect to each other and means including said connecting means for alternately driving the legs through paths extending, for each leg, from a registering position in which its side face engages the lowermost card in the stack forwardly along the path of card movement, upwardly until it clears the lowermost card, and then backwardly above the path of card movement to a gate position in which its side face engages the stack above the lowermost card.

2. Card feeding mechanism for feeding cards from a stack, comprising a walking gate including a frame of U-shaped horizontal cross-section, a pair of legs, a pair of vertically spaced rods spanning said U-shaped frame, said legs being located between the arms of said U-shaped frame and having vertically extending slots in their upper ends to receive the upper rod, said rods supporting said legs for limited horizontal and vertical movement with respect to said frame, each leg having a foot with a side face adapted to engage the leading edges of cards in the stack and a bottom face adapted to engage the top of a card moving under the gate, means connecting said legs for eccentric movement with respect to each other including said rods, vertically extending slots in the upper ends of said legs to receive the upper rod, said upper rod serving as a pivot for said legs and transverse openings in each leg to receive the lower rod, said transverse openings extending horizontally in the direction of movement of said legs, said lower rod limiting the movement of said legs, and means including said connecting means for alternately driving the legs through paths extending, for each leg, from a registering position in which its side face engages the lowermost card in the stack forwardly along the path of card movement, upwardly and until it clears the lowermost card, and then backwardly above the path of card movement to a gate position in which its side face engages the stack above the lowermost card.

3. Card feeding mechanism as defined in claim 2, including spring means biasing said legs to hold one end of said openings in engagement with said lower rod.

4. Card feeding mechanism for feeding a stack of cards,

comprising a walking gate including a frame of U-shaped horizontal cross-section, a pair of legs located between the arms of said U-shaped frame, means supporting said legs for limited horizontal and vertical movement with respect to said frame, each leg having a foot with a side face adapted to engage the leading edges of cards in the stack, and a bottom face adapted to engage the top of a card moving under the gate, means connecting said legs for eccentric movement with respect to each other including a shaft spanning said U-shaped frame and journaled in both said legs, the journal in one leg being eccentric with respect to the journal in the other leg, means pivotally supporting and limiting the movement of said legs within said frame, and means including said connecting means for alternately driving the legs through paths extending, for each leg, from a registering position in which its side face engages the lowermost card in the stack forwardly along the path of card movement, upwardly until it clears the lowermost card, and then backwardly above the path of card movement to a gate position in which its side face engages the stack above the lowermost card.

5. Card feeding mechanism as defined in claim 4, in which said shaft extends freely through one of the arms 25 to the U-shaped frame, and means outside of the frame for driving said shaft including a mechanical connection to permit lateral translation of said shaft.

6. Card feeding mechanism as defined in claim 5, in which said means pivotally supporting and limiting the movement of said legs comprises a pair of rods vertically spaced spanning said U-shaped frame, said legs being located between the arms of said U-shaped frame and having vertically extending slots in their upper ends to receive the upper rod, said upper rod serving as a pivot for said legs, and transverse openings to receive the lower rod, said openings extending horizontally in the direction of movement of said legs, said lower rod limiting the movement of said legs.

7. Card feeding mechanism for feeding cards from a stack comprising, a walking gate including a frame having a U-shaped horizontal cross-section open at one side, a leg received within said U-shaped frame having a U-shaped horizontal cross-section open at the other side, a second leg received within the U-shaped leg, means supporting said legs for limited horizontal and vertical movement with respect to said frame, each leg having a foot with a side face adapted to engage the leading edges of cards in the stack and a bottom face adapted to engage the top of a card moving under the gate, means connecting said legs for eccentric movement with respect to each other and means including said connecting means for alternately driving the legs through paths extending, for each leg, from a registering position in which its side face engages the lowermost card in the stack forwardly along the path of card movement, upwardly until it clears the lowermost card, and then backwardly above the path of card movement to a gate position in which its side face engages the stack above the lowermost card.

8. Card feeding mechanism, comprising a hopper for receiving a stack of cards and having an opening at one end and adjacent the bottom through which cards may move, friction drive means engaging the bottom card and tending to drive it through said opening, and a walking gate at said opening and controlling the spacing of the cards moving therethrough, said gate comprising a frame outside and above said opening, a pair of legs, each leg having a foot with a side face adapted to engage the leading edges of cards in the stack, and a bottom face adapted to engage the top of a card moving under the gate, means supporting said legs for limited horizontal and vertical movement with respect to said frame, means connecting said legs for eccentric movement with respect to each other and means including said connecting means for cyclically and alternately driving the legs through paths extending, for each leg, from a

registering position in which its side face engages the lowermost card in the stack forwardly along the path of card movement, upwardly until it clears the first card, and then backwardly above the path of card movement to a gate position in which its side face engages the stack of cards above the lowermost card, said connecting means being effective when the foot of one leg is in the registering position to hold the foot of the other leg in the gate position, said friction drive means being effective as each foot moves forwardly to carry the lowermost card along with the forwardly moving foot and under the foot in the gate position, and a set of pull-out rollers positioned to engage a card soon after it clears the legs of the gate.

9. Card feeding mechanism comprising a walking gate including a frame, a pair of legs, means supporting said legs for limited horizontal and vertical movement with respect to said frame, each leg having a foot with a side face adapted to engage the leading edges of cards in a stack and a bottom face adapted to engage the top of a card moving under the gate, means connecting said legs for eccentric movement with respect to each other and means including said connecting means for alternately driving the legs through paths extending, for each leg, from a registering position in which its side face engages the lowermost card in the stack forwardly along the path of card movement, upwardly until it clears the lowermost card, and then backwardly above the path of card movement to a gate position in which its side face engages the stack above the lowermost card, a friction drive means for the cards being fed from the stack, said means for driving the legs of the gate operating through a cycle which is completed faster than the friction drive means can push a complete card forward, so that said cards are fed in an overlapped relationship, a support member extending parallel to said stack of cards, a parallelogram linkage connecting said frame to said support member, and means for driving said legs including a first shaft journaled in said legs and extending freely through said frame, a second shaft rotatable about a fixed axis,

two universal joints in series connecting said shafts, and means for driving said second shaft.

10. Card feeding mechanism, comprising a hopper for receiving a stack of cards and having an opening at one end and adjacent the bottom through which cards may move, friction drive means engaging the bottom card and tending to drive it through said opening, and a walking gate at said opening and controlling the spacing of the cards moving therethrough, said gate comprising a frame outside and above said opening, a pair of legs, each leg having a foot with a side face adapted to engage the leading edges of cards in the stack, and a bottom face adapted to engage the top of a card moving under the gate, means supporting said legs for limited horizontal and vertical movement with respect to said frame, means connecting said legs for eccentric movement with respect to each other and means including said connecting means for cyclically and alternately driving the legs through paths extending, for each leg, from a registering position in which its side face engages the lowermost card in the stack forwardly along the path of card movement, upwardly until it clears the first card, and then backwardly above the path of card movement to a gate position in which its side face engages the stack of cards above the lowermost card, said connecting means being effective when the foot of one leg is in the registering position to hold the foot of the other leg in the gate position, said friction drive means being effective as each foot moves forwardly to carry the lowermost card along with the forwardly moving foot and under the foot in the gate position, said leg driving means completing its cycle of operation in a time shorter than that required for the friction drive means to drive a complete card out of the hopper, so that the cards are driven in an overlapped relationship.
